UNITED STATES PATENT OFFICE.

GEORGE R. PLOTT, OF HILLSBORO, NORTH CAROLINA.

BOBBIN-SUPPORT.

1,387,943.

Specification of Letters Patent. Patented Aug. 16, 1921.

Application filed December 1, 1920. Serial No. 427,576.

To all whom it may concern:

Be it known that I, GEORGE R. PLOTT, a citizen of the United States, residing at Hillsboro, in the county of Orange and 5 State of North Carolina, have invented certain new and useful Improvements in Bobbin-Supports, of which the following is a specification.

This invention relates to filling-changing 10 motions for looms and more especially to a novel and improved bobbin support for employment in connection with a filling-changing motion such as is employed in the well-known Northrop loom, one of the primary 15 objects of the invention being to provide means for supporting a bobbin which is in position to be delivered from the hopper of the motion into the shuttle and to provide for such delivery without likelihood of injury to the box or shuttle or imposing any 20 undue wear upon the bobbin.

Another object of the invention is to provide means for yieldably supporting the heel or butt of a bobbin while the bobbin is 25 yet within the hopper of the filling-changing motion and which means, while securely supporting the bobbin prior to transference, will be adapted to readily yield upon action of the transerrer in placing the bobbin 30 within the shuttle.

Another object of the invention is to so construct the device that the same will operate automatically and smoothly and will not be liable to become caught or disarranged but will at all times be capable of 35 operating in a proper and efficient manner.

In the accompanying drawings:

Figure 1 is a sectional view through the right hand end of a portion of a Northrop 40 loom illustrating the usual filling-changing motion, the view showing the device of the present invention in position supporting a bobbin which is in turn in position to be delivered to the shuttle to replace an empty bobbin or in the event of breakage of the filling;

Fig. 2 is a sectional view taken substantially at right angles to the plane of Fig. 1 and illustrating the device of the present invention in elevation and supporting a bobbin;

Fig. 3 is a vertical sectional view taken substantially on the line 3—3 of Fig. 2;

Fig. 4 is a perspective view of the device 55 of the present invention disassembled from

the remainder of the filling-changing motion.

As previously stated, the device embodying the present invention is especially designed for employment in connection with the filling-changing motion of a Northrop loom although not limited to this specific application, and in the drawings there has been illustrated so much of such a loom as is necessary to disclose the invention. Thus in the drawings there is illustrated the hopper of such a loom comprising the inner and outer heads which are indicated respectively by the numerals 1 and 2 and between which the bobbins are supported, the bobbins being indicated by the numeral 3 and each having the usual head 4 which is seated within a recess 5 formed in the peripheral portion of the face of the head 1, and the usual nose 6 which is engaged by a spring retaining element 7 upon the head 2.

The head 1 is provided with a series of the recesses 5, and likewise the head 2 is provided with a series of the spring-retaining elements 7 so that a considerable number of filled bobbins may be supported between these heads comprising the hopper of the motion. In order that the heels 4 of the bobbin may be retained within the recesses 5, the head 1 is rotatably disposed within a circular frame having a projecting flange 8 which closes the open sides of the recesses 5, these recesses opening through the periphery of the head 1. However this flange 8 is interrupted at its lower side as indicated by the numeral 9 so as to provide a throat 10 flanked by an inclined guide 11, it being understood that as usual the bobbins are to be successively discharged or delivered from the hopper through the throat 10 and guided by the guides 11 into the shuttle which is indicated by the numeral 12,

the delivery of a filled bobbin into the shuttle serving to displace the empty or partially emptied bobbin which is at such time within the shuttle and discharge the same through the lower side of the shuttle and through a chute 13 into the usual receptacle 14 provided for receiving the discharged bobbins. The delivery of a filled bobbin through the throat 10 and into the shuttle 12 is effected by the usual transerrer 15 having the usual transerrer fork connection 16, the end of the transerrer arm engaging the heel of a bobbin which is to be 110

delivered, and the fork engaging the nose of such a bobbin. The transferer 15 is actuated in the usual manner through the co-action of the bunter 17 with the latch finger 18 which is connected with the transferer 15, and the transferer 15 carries the usual bow 19 for coaction with the ratchet 20 upon the head 1 of the hopper so that after the transferer 15 and its fork has been 10 swung downwardly to deliver a filled bobbin into the shuttle 12, and the transferer is restored to normal position through the medium of the usual spring 21, the hopper will be rotated a part of a revolution to bring into delivery position another filled bobbin.

The device embodying the invention comprises a pintle 22 which is reduced and threaded at one end as at 23 for the application of a nut 24, this end of the pintle being fitted through a portion of the frame of the loom as shown in Fig. 2 of the drawing and the nut being applied and tightened thereon to secure the pintle in place. Mounted for swinging movement upon and about the pintle 22 is a supporting member which is indicated in general by the numeral 25, this member comprising a sleeve 26 which rotatably fits the pintle 22, and a flat preferably rectangular body 27 which extends radially with relation to the axis of the sleeve. A coil spring 28 is fitted onto the portion of the pintle 22 which projects beyond one end of the sleeve 26 of the supporting member, and one end of this spring is engaged as at 29 about a stud upon the said end of the pintle. The other end portion of the spring is extended beneath the body 27 near its juncture with the sleeve 26 and is hooked as at 30 to engage about one lateral edge of the body and in a notch 31 formed in the said edge.

The device is so positioned that the body 27 of the supporting member will be yieldably supported by the spring 28 in position bearing against the under side of the heel of the bobbin which is in position for de-

livery to the shuttle 12, as clearly shown in Figs. 1 and 2 of the drawings, and it will be understood that upon operation of the transferer 15 and its fork to deliver the filled bobbin, the bobbin in passing into the throat 10, will ride past the end of the body 27 of the supporting member, depressing the same against the tension of the spring 28, this spring serving to immediately return the supporting member to its normal position after the heel of the bobbin has passed the same and so that when another bobbin is brought to delivery position its heel will be supported by the said member. It will be evident that while the supporting member firmly holds the heel of a bobbin which is in delivery position, in its respective recess 5 in the head 1 of the hopper, the device 65 does not in any way interfere with the proper delivery of the filled bobbin to the shuttle. It will also be evident that inasmuch as it is upon the return movement of the transferer 15 that the hopper is rotated 70 to bring the next filled bobbin into delivery position, and all of the bobbins prior to reaching this position are supported by the flange 8, the supporting member 25 will have been returned to its normal or supporting 75 position across the throat 10 prior to such rotative movement of the hopper and will therefore be in a position to receive and support the heel of the bobbin next delivered as the heel of the said bobbin rides off from 80 the end of the flange 8.

Having thus described the invention, what is claimed as new is:

A device for the purpose stated comprising a pintle, a bobbin supporting member 85 comprising a plate formed between its ends with a sleeve pivotally fitting the pintle and having its portions beyond the sleeve in mutual flat contact to provide a supporting leaf, and a spring coiled about the pintle and 90 having operative connection with the leaf to yieldably support the same.

In testimony whereof I affix my signature.
GEORGE R. PLOTT. [L.S.]
